UNITED STATES PATENT OFFICE.

CROSBY FIELD, OF BROOKLYN, NEW YORK, ASSIGNOR TO BRILLO MANUFACTURING COMPANY, INC., A CORPORATION OF NEW YORK.

SCRUBBER SOAP.

Application filed October 8, 1925. Serial No. 61,189.

My present invention contemplates a cake of soap, preferably of the kind ordinarily used for scrubbing, dish washing, etc., having embedded in the cake, preferably by 5 casting, a wad or mass of soft metal ribbons or threads, for which purpose I prefer soft metals such as copper or aluminum or nickel and also various soft metal alloys as, for instance, the softer kinds of brass, bronze, 10 German silver, monel metal, and ordinary tinsel.

I prefer to employ these soft metals in the form of thin, narrow ribbons so that their physical flexibility and shape will permit 15 slipping over the surface to be cleaned, without scoring the surface, except under great pressure which may be easily avoided in practice.

Such metals are non-rusting, and for this 20 reason and also because of their softness, they may be used in the form of metal wool, which may be like steel wool in size, but which will be free from the biting, cutting quality, characteristic of steel wool.

25 The above and other features of my invention will be more readily understood from the following description in connection with the accompanying drawings, in which

Fig. 1 is a perspective view of a cake of 30 soap illustrating one embodiment of my invention;

Fig. 2 is a section on the line 2—2, Fig. 1; and

Fig. 3 is a perspective view of a cake of 35 soap embodying a modification of my invention.

In Figs. 1 and 2, the cake is shown as comprising ordinary soap, 1, which may be formed in a cake of any desired size and 40 shape and which has embedded and extending to the surface thereof, metal ribbons, 2. The width of the ribbon may be, say, eight to twelve times its thickness and, say, $1/_{16}$ to $1/_{64}$ of an inch wide, by, say, $1/_{500}$ to $1/_{100}$ of an inch thick. Such material, especially 45 when made from relatively soft metal such as tinsel, will afford a surface well adapted for washing and mild scrubbing of surfaces to be cleaned, and a satisfactory amount of 50 such surface can be afforded by a relatively small amount of the ribbon. The advantage of this is that as the soap wears down, it does

not become masked by the ribbon as it is uncovered by the dissolving soap. The layer of free ribbon grows thicker, of course, but 55 the soap remains fairly accessible to the end.

An important point is that the thinner the cake of soap becomes, the more effectively the ribbon protects it from being broken up and wasted.

In the form shown in Fig. 3, the relatively soft non-ferrous metal is supposed to be in the form of metal wool, 3. It will be noted as to this material, that it is very stringy and yielding, that the raw edges characteristic of metal wool are of soft material, and that the only backing for the wool is the relatively yieldable material of the soap. Consequently, when such a cake of soap is rubbed on the surface to be cleaned, the soft 70 metal wool cannot attack the surface being cleaned, except under great pressure. The material being more or less hair-like and springy, yields under pressure until it comes in contact with the cake of soap. Thereupon, if attempt is made to apply still greater pressure, the wool will sink into the face of the soap. Consequently, soft metal wool employed in this relation is not usable for purposes which could be served by steel wool. 75 For this very reason, it has its own special advantages for use on surfaces that would be injured by steel wool.

I am aware that it has been proposed to embed carborundum, steel wool and other 80 abrasives in a cake of soap and more specifically that it has been proposed to embed steel wool in a cake of soap having a woolen fabric backing to prevent the steel wool from injuring the hand. In the latter case, the steel 85 wool is employed for its remarkable abrasive quality which is, of course, useful for certain purposes and which is the cause of employment of the woolen cloth backing to protect the hand; also there has been suggestion that 90 crystalline metals such as zinc, or even certain non-ferrous alloys, might be of sufficiently abrasive to be used as a substitute for the steel wool. It will be evident, however, 95 that my invention depends upon using relatively soft metals in extremely flexible forms for the purpose and with the result of avoiding abrasion or scoring of the surfaces to be cleaned and rendering quite unnecessary the 100

woolen cloth backing for protection of the hand. The relatively soft metals may be in the form of metal wool, as shown in Fig. 3, or tinsel-like, in the form of thin-rolled metal ribbon.

I claim:

1. An article of manufacture, comprising a cake of soap having embedded therein a mass of thin, flexible strips of relatively soft, 10 non-abrasive metal.

2. An article of manufacture, comprising a cake of soap having embedded therein a

mass of thin, flexible ribbons of relatively soft tinsel-like metal.

3. An article of manufacture, comprising 15 a cake of soap having throughout the mass and extending through the surface thereof, a wadded mass of rolled relatively soft tinsel-like metal in ribbon form.

Signed at New York, in the county of New 20 York, and State of New York, this 7th day of October, A. D. 1925.

CROSBY FIELD.
